UNITED STATES PATENT OFFICE.

GEORGE T. TRUNDEL, JR., OF CLEVELAND, OHIO, ASSIGNOR TO THE GEO. T. TRUNDEL, JR. ENGINEERING COMPANY, OF CLEVELAND, OHIO, A CORPORATION OF OHIO.

LIFTING JACK.

Application filed October 17, 1924. Serial No. 744,165.

This invention is concerned with lifting jacks and relates to jacks of the double telescoping lift bar type. The general object of the invention is the provision of a compact low clearance jack of the double bar type having an unusual lift but of small height and which is simple in operation.

Another object of my invention is the provision of a double pawl actuated lift bar jack having automatically operable mechanism controlling the relative upward and collapsing movements of the telescoping bars whereby they may be actuated in sequence by operating the pawls in a usual manner.

A further object of my invention is the provision of a jack having a lifting bar comprising a plurality of telescoping members and a pawl actuating mechanism mechanically actuating the elements in sequence and which may automatically telescope when a load is not on the jack, the telescoping movements being consequent to a manual positioning of the pawls.

A still further object of my invention is the provision of a mechanical construction for a double bar lifting jack wherein the center of gravity of the assumed load upon the telescoping elements will be in a vertical plane extending approximately through the ratchet teeth on the bar whereby the stresses between the telescoping elements are reduced to a minimum and the friction therebetween greatly reduced.

Other objects of my invention will hereinafter be set forth in the following description referring to the accompanying drawing illustrating a preferred form thereof. The essential characteristics are summarized in the claims.

In the drawings, Fig. 1 is a side elevation of a double lifting bar jack embodying the features of my invention, the jack being illustrated with the telescoping bar members in extended position; Fig. 2 is a front elevation of the jack shown in Fig. 1; Fig. 3 is an enlarged cross sectional view taken substantially along the line 3—3 of Fig. 1; Fig. 4 is an enlarged cross sectional elevation taken through the jack standard and lifting bars substantially along the line 4—4 of Fig. 3; Fig. 5 is a fragmentary cross sectional view taken through the pawl mechanism substantially along the line 5—5 of Fig. 4; Fig. 6 is a cross sectional view taken

through the pawl mechanism and jack bar showing the cooperative relation of the pawl members when conditioned to elevate the lifting bar in a step by step movement; Fig. 7 is a view similar to Fig. 6 but showing the cooperative relation of the pawl members when conditioned to lower the lifting bar by a step by step movement.

My invention contemplates the construction of a jack having a standard of low clearance or height provided with a plurality of extensible members comprising the lifting bar of the jack which may be elevated and lowered in sequence when carrying a load by a pawl mechanism adapted to actuate the extensible members in a step by step movement. The constructive features of the jack are such that an unusually long jack reach may be obtained and which is readily operated upon the application of a small force and the sequential actuation of the telescoping members comprising the lifting bar mechanism takes place automatically upon the usual actuation of the pawl members by an operating handle.

The arrangement of the telescoping bar members with reference to the standard and the pawl actuating means is such that when the jack bar takes up a load, the thrust of the load is directly upon the lifting pawl and operating lever therefor and the saddle for engaging the object to be lifted is arranged relative to the lifting bar and standard in such manner that the center of gravity of the load will lie in a plane passing through the ratchet teeth on the lifting bar, thus greatly reducing the reactionary forces between the bar elements and between the standard and bar.

As shown in the drawings, I accordingly provide a primary rack bar 8 which is formed to be retained by and slide in a hollow secondary bar member 9 and the latter is formed to slide in the standard 10 and to have teeth in alignment with teeth on the primary bar 8. The secondary member 9 is adapted to be locked to the standard 10 while the bar 8 approaches its completely extended position whereupon it is arranged to engage the secondary bar to bring the teeth thereof into engagement with the pawls. The standard comprises a housing member 10 having a base 12 proportioned whereby it will be bisected by a plane extending through the rack teeth of the bars

and is provided with a hollow offset portion 13 in the front of the jack which constitutes a support for a pivot pin 14 upon which a socketed operating member 15 is pivotally mounted.

The pawl mechanism for actuating the bars may comprise an operating or lifting pawl 18 mounted in the bifurcated end of an oscillatable handle 15 and a detent pawl 17. A pin 14 also comprises a pivotal mounting for the detent pawl 17 which serves to engage the bar and support the load when the lifting pawl 18 is being operated by the member 15. The pawl 18 is pivotally mounted upon a pin 19 secured in the bifurcated end of the operating member 15. A spring member 20 formed at the lower end thereof to engage the jack standard extends over a pin member 23 and upwardly a sufficient distance within the housing portion 13 to engage suitable shoulders formed on both the pawl members whereby they are normally urged into engagement with rack teeth 25 formed on the front faces of the telescoping rack bar members 8 and 9. The teeth 25 of the respective rack bar members are formed to be in alignment and the pawl members 17 and 18 have the rack engaging ends thereof formed to span the combined width of the teeth formed on both whereby at a predetermined elevated position of the inner bar member 8, the actuating pawl 18 will engage teeth on both bar members but until then will engage only the teeth on the inner member as will be hereinafter described.

The raising and lowering operation of the rack bars by the pawl members will now be described. In Figs. 4, 6 and 7, a manually set trip member in the form of a flat lever 30 is shown as being mounted upon the operating lever pivot pin 14. In these figures, a spring 31 is shown formed to engage the front wall of the standard and extend around the pin 23 and upwardly to engage a cam end 32 of the lever member 30. The spring as shown in Fig. 4 will retain the lever 30 as positioned, and in which position the lever 30 does not contact with the pawl members in any manner when the pawl 18 is actuated to raise the bars. The oscillating movement of the member 15 will raise and lower the pawl 18 and the bar will be elevated at each oscillation thereat a distance corresponding to the pitch of the rack teeth. The pawl 17 serves merely as a resilient detent to retain the bar in each of its step by step elevated positions. When it is desired to lower the bar by a step by step movement, the trip lever 30 may be manually swung to the position shown in Fig. 7, whereupon a cam portion 40 thereof will engage a projection 41 on the pawl 17 to draw it out of engagement with the rack bar. This manual shifting of the op-

erating lever 30 however, can only be accomplished when the load upon the rack bar is being taken by the pawl 18 and its operating handle. Thus the pawl 17 will be drawn out of engagement with the rack bar in opposition to the influence of the spring 20 when the operating member 15 is swung upwardly, thus carrying the operating pawl 18 downwardly with the loaded bar in engagement therewith. A shoulder 45 formed on the pawl member 18 contacts with the cam portion 32 of the operating member 30 thus causing the latter to be swung in unison with the movement of the operating member until the pawl 17 takes the load. The trip lever 30 has the cam portion 40 thereof shifted from the projection 41 on the pawl 17 and the latter is permitted to engage a succeeding tooth on the lifting bar. If no load is on the jack bar, the operating member 15 may be brought into alignment with the trip lever 30, causing downward movement of the inner ends of both members simultaneously and the pawls will be brought out of engagement with the lifting bars when the lifting bars are free to drop. It is to be understood that both pawls cannot simultaneously become disengaged from the rack bars if a load is present on the bars.

The mechanical arrangement whereby I obtain an efficient cooperation between the standard, the intermediate rack bar 9 and the primary rack bar 8 will be now set forth. It has been the custom in constructing all jacks of the rack bar type to position the saddle portion of the rack bar relative to the body of the bar with the center of the saddle arranged approximately in alignment with the center of the bar. In the present instance, the saddle portion 70 and the body of the primary bar 8 are arranged so that the saddle center is directly in alignment with the teeth 25 of the bar. The base 12 of the standard is also proportioned relative to the housing portion of the standard so that a vertical plane extending through the center of the saddle portion 70 of the bar 8 bisects the base area. The importance of this arrangement in a jack of the lifting bar type which comprises a plurality of telescoping elements is apparent. By this arrangement, the major thrust exerted upon the jack is taken directly by the pawls and very little friction will exist between the bar elements when relative movement is taking place between the two rack bar members due to reactive forces. This arrangement greatly simplifies the mechanism which is directed to permitting an automatic actuation of the bar members both in raising and lowering and greatly simplifies the construction of the telescopic members.

As shown in Fig. 3 the primary bar 8 has the rear thereof of greater width than

the bar proper to provide longitudinal ribs 72 which engage the secondary bar 9 in longitudinally extending slots formed there-in and the standard is provided with interi-orly disposed longitudinal ribs 80 which engage in slots 81 formed in the side walls of the secondary bar 9. In view of the absence of reactive force and a considerable decrease in friction between them due to the position of the saddle 70 on the bar 8, the bar members 8 and 9 may comprise castings and the sliding surfaces thereof may be accordingly more or less rough without interfering with the proper operation of the jack.

The means for automatically locking the secondary element to the standard and the primary element to the secondary element will now be described. In Fig. 2 it will be noted that at the upper portion 90 on the front face of the secondary element 9, the teeth are omitted. When the secondary element 9 is in a completely telescoped position relative to the standard the face portions 90 of the member 9 are adjacent the tooth engaging end of the operating pawl 18. Thus the operating pawl engages only the teeth of the primary bar 8 until the primary bar is in an approximately completely extended elevation. Carried on the lower end of the bar 8 is a plunger 92 urged normally rearward by a spring 93 against the inner surface of the back wall of the bar 9. The friction created by the action of the spring 93 would normally cause the bar 9 to follow the movement of the bar 8, but I provide a positive stop for the bar 9 in the form of a pivotally mounted detent lever 95, disposed between the back walls of the standard and the bar 8 and extends through a seat form in the bar 9. The upper edge of this detent lever is formed to engage a shoulder of an opening 96 formed in the back wall of the standard, the detent 95 being mounted upon a pin 97 supported by lugs 98 formed on the bar 9. The shape of the detent lever 95 is such that it extends through the slot in the bar 9 with a portion thereof in rubbing contact with the rear face of the bar 8, this rubbing contact being such that it is maintained in a locking position relative to the standard as long as it is in contact with the bar 8. It is accordingly positioned on the bar 9 a considerable distance below the top thereof whereby the lower end of the inner bar 8 will be elevated out of contact with it prior to the locking of the two bars together. At such time, the plunger 92 carried by the bar 8 will have been brought into alignment with an opening 99 formed in the back wall of the bar member 19, whereupon the two members will become automatically locked together and the first upper teeth on the inner bar member 9 will be brought into operative rela-

tion with the operating pawl 18. Both bar members may thus be actuated to complete extensible position until a lug 101, formed on the bottom of the bar 9, contacts with the underside of a transversely disposed plate 102 extending through a suitable opening formed in the rear wall of the standard, the plate being positioned to be in alignment with the opening 99 formed in the bar member 9. A flange bordering the opening 99 is slotted to permit the plate to extend into the opening whereby the upper side 103 of this plate member may serve as a cam to urge the plunger 92 out of engagement with the bar member 99 upon a downward movement of the bar member. In Fig. 6, the bar member 8 is shown in a completely extended position and locked by the plunger 92 to the bar member 9. It will be noted in Fig. 6 that the locking lever 95 is positioned to be out of longitudinal alignment with the plate member 102, whereby this lever will clear the cam when the bar member 9 is completely elevated.

From the foregoing description of my invention it will be readily seen that a jack constructed to embody the features of my invention will be very compact and sturdy, while an unusual elevation in the load lifting member may be obtained; that these members may be operated in sequence and automatically locked together and unlocked only when each member has been actuated to its full movement relative to the other member and that the construction is such that the proper automatic telescoping of the members upon the usual manipulation of a jack operating member is assured by reason of the fact that the load is primarily taken directly on the pawl carried by the operating member thus greatly eliminating the tendency of the telescoping members to bind together and operate out of sequence.

I claim:

1. A lifting jack comprising a standard, a vertically movable lifting bar mechanism mounted in the standard and formed by a pair of telescoping members having adjacently formed rack teeth, an operating member and pawl carried thereby for engaging the teeth of the rack members, means for positively locking one rack member to the standard during a lifting movement of the other rack member, means for automatically locking the two rack members together while the first rack member is approaching a completely extended position relative to the second rack member, said positive locking means being released by the first rack member prior to the locking together of the two rack members by said automatic locking means and means carried by the standard for unlocking the two rack members upon completion of the lowering movement of the second rack member.

2. A lifting jack comprising a base or standard, a load lifting mechanism vertically movable within the standard, operating means for elevating and lowering said lifting mechanism in step by step movements, said lifting mechanism comprising a pair of telescopingly arranged rack bar members having the rack teeth thereof in a common plane, means whereby one rack member is retained in the base while the other is elevated, means for automatically locking the two rack members together upon the complete extension of one of the members, one of said members having a saddle disposed thereon whereby the center thereof lies in a vertical plane extending through the rack teeth of both rack members.

3. In a lifting jack an extensible bar comprising vertically movable members, operating means adapted to lift one of said members independently of the other, a latch carried by one of said members and adapted to cooperate with the other to permit the members to rise in response to movement of said operating means after one of the members has been lifted a predetermined distance and means operable by one of the members for maintaining the other member locked to the standard.

4. A lifting jack comprising a standard, a vertical movable lifting bar mechanism mounted in the standard and formed by a pair of telescoping members having adjacently formed rack teeth, an operating member and pawl carried thereby for disengaging the teeth of the rack members, a swingable member for positively locking one rack member to the standard during a lifting movement of the other rack member, a spring urged plunger carried by one of the members for locking the two rack members together while the first rack member is approaching a completely extended position relative to the second rack member, said swingable member being released by the first rack member prior to the locking together of the two rack members by said plunger and means carried by the standard for retracting the plunger upon the completion of a lowering movement of a second rack member.

5. A lifting jack comprising a base or standard, a load lifting mechanism vertically movable within the standard, operating means for elevating and lowering said lifting mechanism in a step by step movement, said lifting mechanism comprising a pair of telescopingly arranged rack bar members having the rack teeth thereof in a common plane, means whereby one rack member is

retained in the base while the other is elevated, means for locking the two rack members together upon the complete extension of one of the members, one of said members having a spring pressed plunger automatically operable to lock both rack members together upon a full extensible movement of one member and to be automatically retracted upon a full reverse movement of the other bar member.

6. A lifting jack comprising a standard, a vertically movable lifting bar mechanism slidably mounted in the standard and comprising a plurality of telescoping members having adjacently formed rack teeth, an operating member, a pawl carried on the inner end of the member, the pawl being of a width corresponding to the combined width of said plurality of telescoping members, a lever carried by one of the telescoping members for engaging the standard, said lever being controlled by another of said telescoping members, whereby the first named member will be maintained in locked relation to the standard while the second named member is being elevated to a predetermined position relative thereto, a plunger carried by said second named member, the first named member having a socket for receiving the plunger, the socket being spaced relatively to said lever member a distance corresponding to the distance between the plunger position and the lower end of said inner member which carries the plunger.

7. A lifting jack comprising a standard and a plurality of telescoping members having adjacently formed rack teeth, an operating member mounted on the standard, a pawl actuated by the operating member, the pawl being adapted to engage each of said plurality of telescoping members, a locking member carried by one of the telescoping members for engaging the standard, said locking member being controlled by another of said telescoping members whereby the first named member will be maintained in locked relation to the standard while the second named member is being elevated to a predetermined position relative thereto, a locking plunger carried by said second named member, the first named member having a socket for receiving the plunger and a cam for forcing the plunger out of the socket, said cam being mounted on the standard and adapted to extend into the socket of said socketed member when the latter is in its lowered position.

In testimony whereof, I hereunto affix my signature.

GEORGE T. TRUNDLE, JR.
